UNITED STATES PATENT OFFICE.

HERBERT E. BRIDGWATER, OF SYRACUSE, NEW YORK, ASSIGNOR TO REMINGTON TYPEWRITER COMPANY, OF ILION, NEW YORK, A CORPORATION OF NEW YORK.

TYPEWRITING-MACHINE.

1,375,772.

Specification of Letters Patent. Patented Apr. 26, 1921.

Application filed October 8, 1918. Serial No. 329,291.

To all whom it may concern:

Be it known that I, HERBERT E. BRIDGWATER, a citizen of the United States, and resident of Syracuse, in the county of Onondaga and State of New York, have invented certain new and useful Improvements in Typewriting-Machines, of which the following is a specification.

My invention relates to typewriting machines and more particularly to line spacing mechanism therefor.

The main objects of my invention, generally stated, are to provide a simple, compact, light and efficient line spacing mechanism which may be manufactured at comparatively small cost and aids in the construction of a small, light, compact and highly efficient yet comparatively inexpensive portable machine.

To the above and other ends which will hereinafter appear, my invention consists in the features of construction, arrangements of parts, and combinations of devices set forth in the following description and particularly pointed out in the appended claims.

In the drawings wherein like reference characters indicate corresponding parts in the different views,

Figure 1 is an enlarged detail left-hand end view of a carriage equipped with the line spacing mechanism of my invention and showing the parts as they appear in normal position.

Fig. 2 is a like view of the same with parts broken away and showing the devices as they appear at the end of a line feed movement.

Fig. 3 is an enlarged detail vertical sectional view of the regulating member and some of the associated parts, the section being taken on the line $\alpha-\alpha$ of Fig. 1, and looking in the direction of the arrow at said line.

Fig. 4 is an enlarged detail vertical sectional view of the construction with parts omitted, the section being taken on the line $y-y$ of Fig. 6 and looking in the direction of the arrow at said line.

Fig. 5 is an enlarged detail fragmentary front elevation showing the construction at the left-hand end of the platen.

Fig. 6 is an enlarged detail fragmentary vertical sectional view of the construction

taken on the line $z-z$ of Fig. 1 and looking in the direction of the arrow at said line. 55

The mechanism forming the subject matter of this invention is embodied in the present instance in a small, light, portable, top strike typewriting machine, such as is more fully disclosed in the patent to A. W. 60 Smith, No. 1,342,513 dated June 8, 1920. It will be understood however that the invention may be embodied in various styles of typewriting machines.

The platen frame or carriage comprises 65 a base plate 1, preferably of sheet metal, which extends throughout the length of the carriage and is formed with grooved tracks or raceways 2 to receive anti-friction balls or rollers 3 which are likewise received in 70 oppositely disposed grooved rails 4 that are or may be supported for ease shifting movement fore and aft of the machine. The carriage as a whole is thus supported to travel from side to side of the machine carrying 75 with it a cylindrical platen 5. There are two sheet metal angle brackets, one of which is secured to the base 1 at each end thereof and which constitute the end plates for the platen frame or carriage and supports for the platen. Only the angle bracket 6, at the left-hand end of the carriage, is shown but it will be understood that both brackets are in the main alike in construction, each having a foot-piece secured to 80 the base 1 by screws 7 and rivets 8 and an upstanding end plate.

The platen is supported on a removable platen shaft 9 which extends through the platen and through a center bearing opening 90 in a platen head 10 secured to the core of the platen at the left-hand end by screws 11. A cylindrical hub 12 projects outwardly from the platen head and constitutes a bearing for a line spacing wheel 13. This wheel 95 is fixedly, though detachably, connected to the platen head by screws 14. A headed bushing 15 is seated in an opening in the end plate of the bracket 6. The head of this bushing bears against the outer side of the 100 end plate and the inner end extends beyond the plate and receives a collar or washer 16. This washer is secured in place preferably by riveting or swaging the inner end of the bushing as indicated at 17. In this manner the bushing is connected to the end

plate 6 and constitutes a bearing for the platen shaft 9. The washer 16 constitutes an abutment against which the line spacing wheel bears, whereas the inner end of the 5 bushing forms an abutment against which the end of the hub 12 on the platen head 10 bears.

A line spacing lever, designated as a whole by the reference numeral 18 and preferably made of sheet metal, extends to both sides of, or above and below, the platen as best shown in Fig. 2. This lever is pivoted at its lower end to the end plate 6 by a shouldered pivot screw 19 held by a lock nut 20. The pivotal center 19 of the lever is below the platen and said lever is formed at its upper end with an off-set finger piece 21. This lever is preferably curved or is of bow-formation as shown in Fig. 2 so that 15 the finger piece 21 may normally extend forward of the vertical center of the platen, as shown in Fig. 1, without the lever being obstructed in its movement by the platen shaft and washer 16.

From an inspection of Fig. 6 it will be seen that the lever 18 bears against the left-hand end plate of the carriage at the inner side thereof and is supported and guided thereby. An integral finger or arm 22 is 25 formed on the lever about midway in the length thereof and extends parallel therewith on the outer side of the end plate and with which it co-operates to support and guide the lever in its line spacing movements; the end plate being thus embraced on opposite sides by the lever. A wire spring 23 is coiled about a pivot 24 supported by ears 25 formed on the bracket 6. The upper end of this coiled spring is bent 30 around the rear edge of the line spacing lever at 26 so as to exert a forward pressure against the lever to return it to normal position. The other end of the spring is preferably connected to a carriage release lever, 35 not shown, so that the spring has a two-fold function of returning the release lever and the line spacing lever. For the purpose of the present case however the opposite end 27 of the spring is shown anchored 40 against the bracket 6. The lever 18 is limited in its return movement by the cross piece 18^a (which connects the finger 22 to the body of the lever 18) coacting with a stop 6^a formed on the end plate 6 as shown 45 in Fig. 1. An off-set extension 28 is formed on the line spacing lever so as to constitute a support for a pivot 29 of a sheet metal line spacing lever 30. This pawl is formed with a barrel 31 that surrounds the 50 pivot 29. The pawl is slotted to receive a wire spring 32 which surrounds the pivot 29 and is connected at one end 33 to the projection 28 and at its opposite end 34 bears against the upper side of the pawl, tending 55 to force the hook-like engaging end 35 of

the pawl into engagement with the teeth of the line spacing wheel. The pawl is also formed with an integral off-set projection 36 which, as will be seen from an inspection of Fig. 5, extends across the plane of the 70 end plate 6 of the carriage and it is adapted to be brought into contact with an inclined under-cut edge 37 of the end plate at the end of the line spacing movement, as shown in Fig. 2. It will be understood that this 75 part 37 constitutes an abutment, stop, or inclined engaging face 37, which when co-operating with the pawl at the end of the line spacing movement acts in the nature of a cam and stop to force the pawl against, 80 and lock it in engagement with, the line spacing wheel, thus preventing an overthrow of the latter and the platen connected therewith. The co-operating contact edge 38 of the projection 36 on the pawl 85 may be slightly beveled, as shown in Figs. 1 and 2, to better fit it to coact in the manner described with the abutment, stop or cam 37 on the end plate.

The line spacing pawl is normally maintained out of engagement with the teeth of the line spacing wheel by a variable regulating or controlling device which determines the extent of line spacing movement transmitted to the platen by the pawl. This 90 regulating device is designated as a whole by the reference numeral 39 and preferably is made of sheet metal in the nature of a plate pivoted at its lower end on a shouldered pivot screw 40, and attached by said 100 screw to the outer face of the end plate 6 of the platen frame. This regulating device is provided with a contact edge 41 on which the pawl normally bears and which is in the nature of a shield that determines 105 at what point in the throw of the line spacing pawl it is permitted to engage a tooth of the line spacing wheel. The plate 39 in the present instance may be adjusted in the plane thereof around its pivot 40 to either 110 one of two positions shown in Figs. 1 and 2. An off-set finger piece 42 is formed on the regulating device to facilitate its adjustment and suitable means are provided to retain the regulating device in the position 115 to which it may be set or adjusted. In the present instance the plate 39 is preferably resilient, exerting a lateral or outward pressure at the upper end thereof and is slotted at 43 to receive a headed shouldered screw 120 44 or locking projection threaded into a tapped opening in the end plate 6. This screw limits the pivotal movement of the plate in opposite directions and also tends to hold it in its adjusted position. Thus 125 the under side of the head of this screw is beveled, as indicated at 45, for co-operation with the walls of the slot 43 in the regulating member. This slot is formed with slightly enlarged openings 46 at the ends 130

thereof and in which the under beveled side of the head of the screw is adapted to be seated; the resiliency of the plate tending to hold the parts thus engaged and prevent 5 an accidental displacement of the regulating device from the position to which it is set or adjusted. When the regulating device is set in the position shown in Fig. 1, the line spacing pawl is effective to produce 10 a single-tooth line space feed of the wheel 13, whereas when the regulating device 39 is set in the position indicated in Fig. 2, a feed of the wheel may be effected for a distance of two teeth thereof.

15 In order to assure a proper line space feed of the wheel 13, and prevent an accidental displacement of the wheel and platen from the position to which it is moved, I have provided a spring pressed roller detent 47 20 mounted on a pivot 48 in the end of a leaf spring 49, secured by screws 50 to the left-hand bracket 6. This roller detent normally bears against the teeth of the wheel as shown in Fig. 4. In order to release the detent and 25 enable the platen to be turned to any irregular line space position I have combined with the detent a releasing device. This device comprises a sheet metal plate 51 provided with a finger piece 52 and formed with 30 a central opening to enable it to receive a bearing on a hub-like portion 53 of the line spacing wheel 13 and have a pivotal movement concentrically with the platen. This plate has formed in the edge thereof a re- 35 cess 54 that enables the detent roller 47 to engage the teeth of the line spacing wheel as shown in Fig. 4. Adjacent to the recess 54 is a second recess 55 at a greater distance from the axis of the platen than the recess 40 54. A side wall of the recess 54 is in the nature of a cam which coacts with the detent roller 47 when the finger piece 52 is moved down as indicated in dotted lines in Fig. 4, thereby deflecting the detent roller 45 away from the teeth of the line spacing wheel and enabling the roller to be seated in the recess 55 where it is held out of co-operation with the teeth of the wheel. A second plate 56 is riveted at 57 to the releasing 50 plate 51 and has a central opening therein to provide an additional bearing for the releasing device on the periphery of the platen head as shown in Fig. 6. It will be understood that a movement of the releasing 55 device to releasing position is effective to throw off the detent roller in the manner described, and that the pressure of the spring 49 of said detent roller is then exerted against the releasing device and by the latter 60 against the periphery of the platen head and against the line spacing wheel secured to the platen head. I thus provide an effective retarding device or brake to hold the platen frictionally in any desired irregularly 65 spaced position to which it may be turned.

When the detent is seated in the depression 55 in the releasing device the pressure of the spring 49 holds the releasing device against displacement from the position to which it has been set and holds it against its 70 tendency to turn with the platen. When the detent is received in the depression 54 in the releasing device said detent will prevent the releasing device from turning with the platen and from being displaced from its 75 normal position. By applying the action of the spring 49 to the periphery of the platen head I am enabled to produce an effective brake near the periphery of the platen.

I preferably form the plate 56 with a de- 80 pending segmental portion 58 which extends beyond the periphery of the platen at the lower portion of the latter and up to the rear side thereof where the work sheets are introduced into the machine. The paper 85 apron 59 of the machine is shown in part in Figs. 5 and 6 from which it will be seen that the left-hand end of the paper apron terminates about coincident with the left-hand end of the platen. The part or flange 58, as 90 will be seen, extends beyond the platen near the left-hand end thereof and prevents the work sheet from extending over into the field of the line spacing mechanism. In short the part 58 acts in the nature of a side 95 edge gage which prevents paper introduced into the machine from fouling on the line spacing mechanism and assures its proper introduction relatively to the platen.

I prefer to form the left-hand end plate 100 with an off-set finger piece 60 in line fore and aft of the machine with the finger piece 21 of the line spacing lever so as to facilitate an actuation of the line spacing lever by grasping the finger pieces 21 and 60 with 105 the thumb and index finger respectively of the left-hand and exerting a pinching pressure on the finger pieces. This also enables the operator to more effectively control the carriage in the return movement of the latter 110 without removing the hand from engagement with the finger pieces.

By pivoting the line space lever 18 on a different axis from that of the platen and at a point remote from the line space pawl, 115 as shown and described, a desirable construction is provided in which only a comparatively small angular motion of the lever is necessary to effect a line space operation.

What I claim and desire to secure by Letters Patent, is:—

1. In a typewriting machine, the combination of a line space wheel, a line space lever the body portion of which bears against one side of an end plate of the 125 platen frame, a guide finger on said lever which bears against the other side of said end plate, and a line space pawl carried by said lever.
2. In a typewriting machine, the combi- 130

- nation of a line space wheel, a sheet metal line space lever pivoted to an end plate of the platen frame and formed so as to embrace said end plate on opposite sides and 5 be supported and guided thereby, and a line space pawl controlled by said lever.
3. In a typewriting machine, the combination of a line space wheel, a sheet metal line space lever extending to opposite sides 10 of the platen and pivoted at one end to an end plate of the platen frame and provided with a finger piece at its opposite end, said lever being formed so as to embrace said end plate and coact therewith on opposite 15 sides and be supported and guided thereby, and a line space pawl pivoted directly to and carried by said lever.
4. In a typewriting machine, the combination of a line spacing wheel, a line spacing pawl, and variable means for determining 20 the extent of line spacing movement transmitted to the wheel at each actuation of the pawl, said means comprising a pivotally mounted resilient controlling plate 25 with which the pawl coacts, said plate having an aperture in the resilient body portion thereof, and a locking projection received in said aperture to limit the pivotal movement of the plate and with which the 30 plate is maintained engaged by the lateral deflection of the body portion thereof due to its resiliency, whereby the plate is held in the position to which it may be adjusted.
5. In a typewriting machine, the combination of a line spacing wheel, a line spacing pawl, and variable means for determining 35 the extent of line spacing movement transmitted to the wheel at each actuation of the pawl, said means comprising an adjustable resilient plate having a slot therein with enlarged openings at its ends, a screw which extends into said slot and has a bevel head that coacts with the walls of 40 said enlarged openings to retain the plate in either set position to which it may be 45 adjusted, the resiliency of the plate maintaining an engagement between the plate and the beveled head of the screw.
6. In a typewriting machine, the combination 50 of a platen, a line space wheel, a spring pressed roller detent which bears against the teeth of the line space wheel, a circular bearing member approximately the size of the line-space wheel and which is 55 fixed to the platen adjacent to one end thereof, and a hand actuated detent releasing device that completely surrounds said circular bearing member and is supported by and mounted for pivotal movement thereon, said 60 releasing device having a cam which coacts with said detent to release it from the teeth of the line space wheel and cause the pressure of the spring of the detent to act on the periphery of said circular bearing 65 member.
7. In a typewriting machine, the combination of a platen, a line spacing wheel, a spring-pressed roller detent which bears against the teeth of the line spacing wheel, and a detent releasing device supported independently of the detent and pivoted to turn around the axis of the line spacing wheel and cause the pressure of the spring of the detent to retard the platen when the detent is thrown off, said releasing device 70 having two recesses that extend in toward the axis of the platen, one in which it is received when the detent acts on the teeth of the wheel and the other receiving the detent when the latter is released, whereby the 75 releasing device is held by the detent against rotative movement in either direction in either position to which said device may be adjusted.
8. In a typewriting machine, the combination 80 of a platen, a line spacing wheel, a spring-pressed roller detent which bears against the teeth of the line spacing wheel, and a detent releasing device pivoted to turn around the axis of the line spacing wheel, 85 said releasing device extending beyond the periphery of the platen and constituting a gage with which a side edge of a work sheet may contact.
9. In a typewriting machine, the combination 90 of a platen, a line spacing wheel, a spring-pressed roller detent which bears against the teeth of the line spacing wheel, a detent releasing device pivoted to turn around the axis of the line spacing wheel, 95 and a segmental depending flange carried by said releasing device and extending beyond the periphery of the platen at and near the introductory side thereof and forming a gage for a side edge of a work sheet. 100
10. In a typewriting machine, the combination of a platen frame, a line space wheel, a hand actuated line space lever pivoted to an end plate of the platen frame, a sheet metal line space pawl carried directly by said lever and formed with an off-set projection, and an undercut stop formed in the edge of said end plate and with which 110 said projection always engages at the end of its stroke to arrest the pawl and positively lock it against disengagement from the teeth of the wheel thus preventing overthrow of the latter and the platen controlled thereby irrespective of the extent of line spacing movement of the platen. 115
11. In a typewriting machine, the combination of a line space wheel, a sheet metal line space lever pivoted to an end plate of the platen frame and formed so as to embrace said end plate on opposite sides and 120 be supported and guided thereby, a line space pawl controlled by said lever and formed with an integral off-set projection, and an undercut combined locking and stopping portion formed integral with said end 125 130

plate and which is always engaged by said off-set projection irrespective of the extent of the line space to limit the feed movement of the pawl and lock it in engagement with the teeth of the wheel and thereby prevent overthrow of the line space wheel and the platen controlled thereby.

12. In a typewriting machine, the combination of a platen, and line spacing mechanism therefor made entirely of sheet metal, said line spacing mechanism comprising a sheet metal lever pivoted at one end and provided at its opposite end with a finger piece, a sheet metal pawl pivoted to said lever intermediate its ends, and an adjustable sheet metal regulating device with which the pawl coacts and which determines the point in the throw of the pawl when it may engage the line space wheel.

13. In a typewriting machine, the combination of a platen, and line spacing mechanism therefor made entirely of sheet metal, said line spacing mechanism comprising a

sheet metal lever pivoted at one end and provided at its opposite end with a finger piece, a sheet metal pawl pivoted to said lever intermediate its ends, an adjustable sheet metal regulating device with which the pawl coacts and which determines the point in the throw of the pawl when it may engage the line space wheel, an integral off-set projection formed on said pawl, and a sheet metal end plate of the platen frame formed with an integral combined locking and stop surface with which said projection on the pawl engages to limit the feed movement of the pawl and lock it in engagement with the teeth of the line space wheel.

Signed at Syracuse, in the county of Onondaga and State of New York, this 1st day of Oct., A. D. 1919.
